UNITED STATES PATENT OFFICE.

STACY B. HASELTINE, OF CHICAGO, ILLINOIS, ASSIGNOR, BY MESNE ASSIGNMENTS, TO
W. H. MINER, INC., A CORPORATION OF DELAWARE.

ANTIFRICTION BEARING.

Application filed January 21, 1924. Serial No. 687,527.

This invention relates to improvements in anti-friction bearings.

One object of the invention is to provide an anti-friction bearing of simple, efficient and economical construction, adapted to be used in railway cars, and employing a rolling anti-friction element, which is automatically centered under the influence of gravity and the action of spring pressure, both working in conjunction.

In the drawing forming a part of this specification, Figure 1 is a vertical sectional view taken lengthwise of the car through the ends of the body and truck bolsters and showing my improvements in connection therewith. And Figure 2 is a vertical sectional view corresponding to the section line 2-2 of Figure 1.

In said drawing, 10 denotes the upper portion of a truck bolster, and 11 the underside of the opposed body bolster of a railway car. The improved bearing is shown applied to the truck bolster and comprises, broadly, a retaining member or housing A; an anti-friction element proper B; a supporting block C; and spring plates D—D.

The retaining member A, preferably in the form of a casting, is formed with end walls 12 and side walls 13, the latter being laterally offset to provide guides 14, as shown. Lugs 15 are provided on the casting for securing the same to the truck bolster by means of rivets or other suitable securing means.

The anti-friction element B consists of a main or central roller portion 16 and end wings or counterweights 17 at each end thereof and integral therewith. The lower edge of each counterweight is substantially flat for a short distance either side of center, the remainder being curved or arcuate and of a somewhat greater radius than that of the central portion 16 of the anti-friction element. Each of the counterweight portions 17 projects into the corresponding guide 14 provided at the sides of the housing. The bounding walls of the guides are shaped to conform to the lines generated by the counterweights during the rolling movement of the anti-friction element with a slight additional working clearance, so that lateral bodily shifting of the counterweights with respect to the retaining member is substantially prevented. Any bodily shifting of

the anti-friction element longitudinally of itself is practically prevented because the counterweights are of such a thickness that they extend to closely adjacent the opposed walls of the retaining member.

The bottom block C is arranged within the retaining member, the same preferably having a hardened wear plate 18 on its top to engage and support the center portion 16 of the anti-friction element. Intermediate the ends of the block C substantially centrally thereof and integral therewith, one on each side, are a pair of ridges or fulcrum projections 19, one extending into each of the guideways below the counterweight extensions 17.

Spring plates or leaf springs D are arranged one on each fulcrum part 19, the upper faces of the free ends of the springs normally engaging horizontally extending abutments or shoulders 20 provided on the housing as shown in Figure 1. There is sufficient clearance between said abutments and the bolster surface 10 so that these spring plates may be flexed downwardly about the fulcrum when the counterweights 17 roll thereon. The springs are prevented from endwise shifting on account of the vertical walls extending downwardly from the shoulders or abutments 20 of the retaining member and are prevented against shifting laterally by the wear plate 18 and the side walls of the retaining member.

In operation, the anti-friction element proper is engaged by the under surface 11 of the body bolster, rolling said element toward one extreme position as shown in dotted lines in Figure 1 (assuming that the direction of the movement of the bolster 11 is to the left), the counterweights 17 rolling on their spring plates to cause the flexing thereof downwardly at one end about the fulcrums 19, the other free ends of the spring plates being rigidly held against upward movement by engagement with their respective abutments or shoulders 20. As soon as the load is released, the downwardly flexed ends of the spring plates D automatically return to their normal position, and acting in conjunction with the influence of gravity on the tilted counterweights, bring the anti-friction element back to its normal central position, thus making the return of the anti-friction element unusually sensitive and

rapid and overcoming any slight amount of friction which may arise between the centering counterweights and the guides.

As the springs always engage the counterweight portions of the anti-friction element on the flat part thereof when in normal central position, they tend to prevent any appreciable oscillation of the latter when not under load, because such oscillation must necessarily be against the pressure of said springs. Therefore, the roller is always in central position so as to furnish its full travel.

I have herein shown and described what I now consider the preferred manner of carrying out my invention, but the same is merely illustrative and I contemplate all changes and modifications that come within the scope of the claims appended hereto.

I claim:

1. In an anti-friction bearing, the combination with a retaining member provided with a bearing surface; of an anti-friction element adapted to roll to either side of normal central position on said bearing surface, said element being provided with counterweight means for centering the same, and resilient means co-operating with said counterweight means and operated by the movement of the same, said counterweight means and said resilient means being mounted so as to exert a combined resilient and gravitational effect upon said anti-friction element without interference of one with the other.

2. In an anti-friction bearing, the combination with a retaining member provided with a bearing surface; of an anti-friction element adapted to roll to either side of normal central position on said bearing surface, said element being provided with eccentric portions having engaging surfaces extending tangentially with reference to the bearing surface of said anti-friction element; and resilient means associated with said retainer and adapted to be flexed by engagement with the bearing surfaces of said eccentric portions.

3. In an anti-friction bearing, the combination with a retaining member adapted to be secured to a bolster or the like; of an anti-friction element adapted to roll to either side of normal central position; leaf springs mounted in said retainer and fulcrumed intermediate their ends, said ends being lim-

ited against movement in one direction; and counterweight portions eccentrically mounted with reference to said element and having engaging surfaces extending tangentially with reference to the bearing surface of said element, said engaging surfaces being adapted to flex opposite ends of said leaf springs dependent upon direction of movement of said element.

4. In an anti-friction bearing, the combination with a retaining member having guides at its sides, each of said guides being provided with oppositely arranged offset shoulders; of a bearing block having centrally arranged laterally projecting ridges; leaf springs arranged in each side of said retainer and having the opposite end portions thereof disposed beneath said shoulders, and each having an intermediate portion resting upon a ridge; an anti-friction element mounted on said bearing block and adapted to roll to either side of central position with reference thereto, said element being provided with laterally extending counterweight sections arranged in said guides, and having bearing surfaces arranged tangentially with reference to the bearing surface of said element, the bearing surfaces of said counterweight sections being adapted to engage said leaf springs so as to independently flex opposite end portions thereof dependent upon the direction of movement of said element.

5. In an anti-friction bearing, the combination with a retaining member provided with a bearing surface; of an anti-friction element adapted to roll to either side of normal central position on said bearing surface, said element being provided with eccentrically disposed counterweight sections at opposite ends thereof, said retainer being provided with guide means for said counterweight sections; resilient means secured in said retainer, said counter-weight sections having actuating portions therein engaging said resilient means to flex the same by movement of said anti-friction element to either side of central position to thereby exert a returning force upon said element.

In witness that I claim the foregoing I have hereunto subscribed my name this 16th day of January, 1924.

STACY B. HASELTINE.
